UNITED STATES PATENT OFFICE.

NORMA FRED SCHAFUSS, OF NEW YORK, N. Y.

CLASP.

1,117,914.

Specification of Letters Patent. Patented Nov. 17, 1914.

Application filed February 12, 1913. Serial No. 747,924.

To all whom it may concern:

Be it known that I, NORMA F. SCHAFUSS, a citizen of the United States, and a resident of the city of New York, borough of Brooklyn, in the county of Kings and State of New York, have invented a new and Improved Clasp, of which the following is a full, clear, and exact description.

The object of the invention is to provide 10 a new and improved clasp more especially designed for use on hose supporters and like devices and arranged to securely grip hose or other fabric material without danger of tearing it.

15 In order to accomplish the desired result use is made of a plate having spaced bearings and coacting clamping members for clamping the fabric material between them, one of the clamping members having long 20 side arms and the other clamping member having short side arms, the side arms of both clamping members terminating in pivots engaging the said spaced bearings to allow of swinging the clamping members 25 independently one of the other into clamping or into open position, the clamping member having the short side arms being adapted to pass between the long side arms 30 of the other clamping member and to the front thereof to overlie this clamping member.

A practical embodiment of the invention is represented in the accompanying drawings forming a part of this specification, in 35 which similar characters of reference indicate corresponding parts in all the views.

Figure 1 is a front elevation of the clasp; Fig. 2 is a transverse section of the same on the line 2-2 of Fig. 1, and showing the 40 fabric material engaged by the clamping members; Fig. 3 is a cross section of the clasp with the clamping members in open position; Fig. 4 is a front elevation of two connected clasps attached to a hose; Fig. 5 is a front elevation of the clasp provided 45 with a supporting loop for single attachment to a hose; and Fig. 6 is a similar view of the clasp attached to a supporting tape.

A plate A of sheet metal or other suitable 50 material is provided at its upper end with a bearing C and at the lower end with a bearing D. The bearing C is engaged by pivots E extending inwardly from long side arms E' connected with each other at their 55 free ends by a clamping member E² co-act-

ing with a similar clamping member F for clamping the hose or other fabric material G between the said clamping members, as plainly indicated in Fig. 2. The clamping member F is provided with short side arms 60 F' terminating in inwardly-extending pivots F² engaging the lower bearing D so that the two clamping members E² and F are free to swing on the plate A independent 65 one of the other, but the side arms E' and F' of the said clamping members are so arranged that the clamping member F overlies the clamping member E² when the clamping members are in clamping position, as indicated 70 in Figs. 1 and 3. The clamping member F is of a length to readily pass between the side arms E' of the other clamping member E², and the side arms F' are bent downwardly, outwardly, inwardly and upwardly 75 to form stops F³ adapted to abut against the back of the side arms E' to limit the forward swinging movement of the clamping member F when passing the latter between the side arms E' (see Fig. 3). The upper 80 ends of the side arms F' are provided with cam faces F⁴ adapted to engage in side arms E' with a view to forcing the same outwardly to allow the plate A to swing forwardly turning on the pivots E as a fulcrum so that the plate A moves into locked 85 position relative to the clamping members E² and F at the time the said clamping members clamp the material G between them, as indicated in Fig. 2. It will be 90 noticed that when the parts are in this position the pivots F² extend forward of a straight line passing through the pivots E and the clamping member F so that the several parts are held in locked position at the time the material G is clamped between the 95 clamping members E² and F. It is understood that by making the arms F' shorter than the side arms E' and providing separate bearings for the said arms to swing on it is evident that the clamping member F 100 can be readily passed between the side arms E', as previously explained and indicated in Fig. 3.

In practice, two such clasps are preferably used on each hose at opposite sides 105 thereof, as plainly indicated in Fig. 4, and in order to connect the clasps with the top of a hose supporter the following arrangement is made: Pivots mounted on the right-hand pivot E of a clasp adjacent the 110

plate A is a socket H in which is secured one end of an elastic or other cord I passing through an eye J pivoted on the left hand pivot E of this clasp, it being understood that the cord I passes through the eye J on the other clasp, and has this end attached to the corresponding socket H; thus by the arrangement described a loop is provided on each clasp between the socket H 10 and the corresponding eye J for engagement with an attaching member of a hose supporter, and the cord I extends over the knee portion and additional attaching members can be connected with the cord intermediate 15 the buckles, as indicated in Fig. 4. By the arrangement described an even pull is exerted on the clasps, and as the clamping members E² and F² grip a large portion of the fabric material G, it is evident that the 20 hose is securely gripped and the danger of tearing is reduced to a minimum. For single attachment of a clasp to hose (see Fig. 5), the pivots E are both pivoted in socket members H', and in the said socket members are 25 secured the ends of a cord I' of elastic or non-elastic material. The sockets H and J are each formed of a flat strip of metal bent at each end in an eye or socket, one of which receives the pivot E and the other the elastic 30 cord I.

The clasp may be directly attached to a strap or tape K of a hose supporter, and for this purpose use is made of a loop L attached to the plate at the upper end thereof 35 to receive the tape K, as plainly indicated in Fig. 6.

In using the clasp the clamping members E² and F are swung into open position (see Fig. 3) and then the fabric material is 40 drawn over the clamping member F from the rear to the front thereof, after which the clamping member F is swung forward between the side arms E' with a view to move the clamping member F to the front 45 of the clamping member E². The user now exerts a forward pressure on the plate A to swing the same forward, the plate turning on the pivots E as the fulcrum. On swinging the plate A forward the pivots F² of 50 the side arms F' are likewise moved forward so that the stops F³ finally abut against the side arms E' and the cam faces F⁴ push the side arms E' apart until the cam faces F⁴ pass to the front of the side arms E', 55 after which the latter by their resiliency swing back to original position so that the cam faces F⁴ overlie the side arms E' at the front while the stops F³ abut against the rear of the said side arms E'. The several parts are now in locked position and 60 the material G is firmly clamped in place between the clamping members E² and F. When it is desired to open the clasp with a view to release the fabric material G the user presses rearwardly on the lower por-

tion of the plate A to force the cam faces F⁴ back to the rear of the yielding side arms E' and to draw the clamping member F upward away from the clamping member E², to permit of finally swinging the clamping member F rearwardly to completely release the fabric material. 70

The clasp shown and described is very simple and durable in construction and composed of comparatively few parts, 75 which can be readily manipulated to securely grip the hose or other fabric material, or to release the same whenever it is desired to do so by opening the clasp and correspondingly pressing the plate A. 80

Having thus described my invention, I claim as new and desire to secure by Letters Patent:

1. A clasp, comprising a plate having bearings at its upper and lower ends, a clamping member having its side members bent inwardly to form pintles engaging the bearing at the upper end of the plate, a second clamping member having its side members bent inwardly to form pintles engaging the bearing at the lower end of the plate, the said side members being also bent downwardly, outwardly, inwardly and upwardly to form a laterally projecting stop on each side member for engaging the lower faces 95 of the side members of the first clamping member, and a loop pivotally mounted with respect to the plate.

2. A clasp, comprising a plate having bearings at opposite edges and co-acting 100 clamping members for clamping a fabric material between them, one of the said clamping members having long side arms and the other clamping member having short side arms, the side arms of both clamping members terminating in inwardly extending pivots engaging the said bearings to allow of swinging the clamping members independently one of the other into clamping or into open position, the clamping member having short side arms being adapted 105 to pass between the long side arms of the other clamping member and to the front thereof and to overlie this clamping member, the said short side arms having outwardly-extending stops adapted to abut 110 against the long side arms at the rear thereof, and the short side arms having outwardly-extending cam faces between the stops and the pivots to engage the long side 115 arms and bend the same outward.

3. A clasp, comprising a plate having spaced bearings and co-acting clamping members for clamping a fabric material between them, one of the said clamping members having long side arms and the other clamping member having short side arms, the arms of both clamping members terminating in inwardly extending pivots 125 engaging the said spaced bearings to allow of 130

swinging the clamping members independently one of the other into clamping or into open position, the clamping member having the short side arms being adapted to pass between the long side arms of the other clamping member and to the front thereof and to overlie the clamping member, an elastic cord and fastening members pivotally mounted on the pintles of one of the clamp-

ing members and engaging the ends of the 10 cord.

In testimony whereof I have signed my name to this specification in the presence of two subscribing witnesses.

NORMA FRED SCHAFUSS.

Correction in Letters Patent No. 1,117,914.

It is hereby certified that the name of the patentee in Letters Patent No. 1,117,914, granted November 17, 1914, for an improvement in "Clasps," was erroneously written and printed as "Norma Fred Schafuss," whereas said name should have been written and printed *Norma Ford Schafuss*; and that the said Letters Patent should be read with this correction therein that the same may conform to the record of the case in the Patent Office.

Signed and sealed this 1st day of December, A. D., 1914.

[SEAL.]

R. F. WHITEHEAD,
Acting Commissioner of Patents.
